DESIGN FOR A WASHING MACHINE

Andrew H. Gerhardt, Skokie, and Arthur P. Schulz, Hinsdale, Ill., assignors to Electric Household Utilities Corporation, Chicago, Ill., a corporation of Illinois

Application February 5, 1945, Serial No. 117,775

Term of patent 14 years

(Cl. D49—1)

To all whom it may concern:

Be it known that we, Andrew H. Gerhardt and Arthur P. Schulz, citizens of the United States, residing respectively at Skokie and Hinsdale, in the counties of Cook and Du Page, and State of Illinois, have invented a new, original, and ornamental Design for a Washing Machine, of which the following is a specification, reference being had to the accompanying drawings, forming a part thereof.

In the drawings:

Fig. 1 is a perspective view showing the front, side and the top of a washing machine embodying our new design.

Fig. 2 is a perspective view taken in opposite relation to Fig. 1, showing the rear, the other side, and a portion of the top thereof.

Fig. 3 is a top plan view thereof on a reduced scale.

Fig. 4 is a fragmentary view in elevation, of the upper portion of the washing machine embodying our new design.

We claim:

The ornamental design for a washing machine, substantially as shown.

ANDREW H. GERHARDT.
